Primary Examiner — Cynthia R Underwood

(74) Attorney, Agent, or Firm — Larson & Larson, P.A.;
Justin P. Miller; Frank Liebenow(57) **CLAIM**

I claim the ornamental design for a bowl, as shown and described.

DESCRIPTION

FIG. 1 is a perspective view of a bowl showing my new design;

FIG. 2 is a back elevation thereof;

FIG. 3 is a front elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a second perspective view thereof, showing the bowl.
